COMBINED FUSE AND CURRENT LIMITING RESISTOR

Elliot Bernstein, Cedarhurst, N. J.

Application April 19, 1956, Serial No. 579,385

5 Claims. (Cl. 200—135)

My present invention relates to fuses for use in electronic circuits, particularly home television receiver circuits.

My invention is directed to a fuse which will have all of the necessary safety characteristics in protecting the circuits while at the same time it will have a sufficiently high temperature co-efficient (increased resistance with increased heat and current) so that an appropriate time lag will be introduced to permit minor and expected surges of energy to be cleared without blowing the fuse and yet any increase in the current value either beyond a predetermined amount or beyond a predetermined time delay period will result in blowing the fuse.

Standard fuses at present used for home electronic purposes, such as television, will almost invariably blow on a minor momentary surge of high amplitude which is so short in duration as to create no probability that any of the circuits would be damaged. Further, such prior fuses tend to derate under ambient temperatures above normal or when operated close to their maximum rating so that they will cause outages on the occurrence of minor surges, and sometimes even without the occurrence of an overload.

Since standard practice requires that such fuses, particularly in home operated devices, be so arranged that they require a trained serviceman to replace them such relatively minor momentary surges in energy will frequently result in an outage requiring a service correction at great expense either to the manufacturer who has guaranteed service or to the consumer who must obtain such service.

Essentially my invention contemplates the utilization of a high temperature co-efficient wire as a fuse wire, which wire, however, is not melted directly by the increased heat generated therein by increased current; but the wire is used primarily to provide a resistance which will rise in accordance with the rate of the current. The wire is so wound that it has preferably the minimum necessary contact with any support so that transfer or drawing off of heat by conduction by outside mounting elements is obviated (the ideal condition being a wire which is completely unsupported except at the ends).

Since the wire is of sufficient length to create the desired resistance characteristics, it is usually utilized in coil form or other wound form in order to reduce the size of the fuse to appropriate commercial dimensions.

The high temperature co-efficient wire has the characteristic that its resistance when cold is at a minimum. A flash-over current heats the wire to increase the resistance thereby limiting the amplitude of the discharge and limiting the rate of rise of the heat. Fault current when it occurs over a minimum period of time (such time may be measured in seconds or fractions of seconds) will generate sufficient heat owing to increasing resistance of the wire to result in a blowing of the fuse.

My invention further contemplates that the blowing of the fuse will not depend per se on the rupture or melting of the wire when heated, but in order to ensure that the rupture of the wire and the blowing of the fuse will take place when the predetermined wire temperature is reached, I place one or more beads of a chemical compound adapted to decompose rapidly under predeter-

2

mined heat conditions on the wire. By using the chemical bead, I am able to use a thicker wire that will remain relatively cool and, therefore, stable in resistance at steady-state currents.

5 The specific composition of this bead will be hereinafter described but essentially it is a combination of magnesium powder, silica powder, barium peroxide powder and a dehydrated nitrocellulose lacquer.

Accordingly utilization of the bead in connection with 10 the high temperature co-efficient wire make it possible to have a fuse which is a current limiting resistor thereby tending to limit any flash-over currents while at the same time it is a fuse which will open the circuit under appropriate fault conditions.

15 As previously pointed out, the effective temperature co-efficient of the resistance wire is limited by any contact with a coil form which may draw off or dissipate the heat in the wire. Thus, for instance, my fuse is so arranged that in a case where normal current may be

20 of the order of 200 milli-amperes, a flash-over current which would otherwise increase the load by 150 amperes will in a milli-second or less be limited to a much smaller rise. Thus, with a basic resistance of 2 ohms

25 in a usual fuse, and a discharge of 300 volts, the surge would be 150 amperes. However, my novel unit, with its inherent resistance of 20 ohms, immediately limits the current to 15 amperes and then responds to the rate of rise of heat and promptly increases resistance to further limit the surge.

30 However, a fault current of 250 percent (500 milli-amperes) lasting over a period of time say of the order of 10 seconds, will result in opening of the circuit. As the fault current becomes higher, there is a progressive decrease in time.

35 I have also found that by winding a 20" wire of .0035" on a 1" form where the wire has minimum contact with the form, I produce a fuse in which the fuse wire has a 20 ohm resistance at normal operating currents of 200 milli-amperes and that this resistance

40 effectively becomes 150 ohms at a 300 volt surge. The wire itself is a standard wire known to have increased resistance with increased temperature and is formed of either iron or nickel, or an alloy of iron and nickel, or of tungsten, and is known in the industry as Hi-Tempco or Balcon No. 236 alloy, .0035" in diameter.

45 Such a wire may be oxidized for two purposes: (1) for insulation; and (2) to create a thermal barrier in order to increase the thermal lag.

Essentially therefore my invention combines two important concepts in a single structure. The arrangement and mounting of the wire to decrease to the absolute minimum any thermal lag in the wire so that the increased heat of the wire in response to increased currents thereby increasing the resistance will create an automatic current limiting resistor; at the same time the utilization of the rupturing bead on the wire which will decompose rapidly at predetermined temperatures turns this current limiting resistor into a fuse.

50 The primary object of my invention therefore is the provision of a combined current limiting resistor and fuse.

55 Another object of my invention is the arrangement of a current limiting resistor so that the conductive-element thereof will be mounted in such manner as to limit its physical and thermally conductive contact to the minimum necessary for actual support of the wire.

60 Another object of my invention is in combination with a wire which responds thermally to any increase in current to utilize a fast thermally decomposing bead of material on the wire in order to rupture the wire when a predetermined current value or predetermined time times current value is reached.

The foregoing and many other objects of my invention will become apparent from the following description when taken in connection with the drawings in which

Figure 1 is a view of a high temperature coefficient conductive wire with a thermal bead thereon.

Figure 2 is a view of a wire arranged in appropriate coil form supported in air with the bead thereon.

Figure 3 is a view in perspective showing one form of coil support with the beaded wire coil thereon, the said coil support being so arranged as to create minimum contact with the wire.

Figure 4 is a cross-sectional view of a coil support slightly modified in structure from the coil support of Figure 3 in order to further decrease the areas of contact between the wire and the coil support.

Figure 5 is a cross-sectional view of another modified form of coil support.

Figure 6 is another modified form of coil support.

Figure 7 is a view in expanded perspective showing one way in which the coil and coil support may be housed in a manner which maintains the coil out of contact with the casing.

Figure 8 is a view in perspective of another form of housing for the coil support.

Figure 9 is a view in perspective of another form of housing of the coil support.

Figure 10 is an exterior view of the housing of Figure 9.

Figure 11 is a plan view of a chassis socket to which the coil in the housing of Figure 10 is to be connected. It should be noted that by appropriate spacing of the prongs of the housing of Figure 10 and of the socket openings in the chassis of Figure 11, only the proper combined current limiting resistor and fuse having properly spaced prongs may be connected in circuit.

Figure 12 is a view of a modified exterior housing construction having a key intended to limit the insertion of the combined current limiting resistor and fuse into only a particular socket.

Figure 13 is a plan view of a chassis with socket openings intended to receive only predetermined key formations.

Figure 14 is an expanded view of another modified form of the coil housing.

Referring first to Figure 1, I have here shown the basic concept of my combined fuse and current limiting resistor in which the wire 10 is a high temperature coefficient wire of appropriate material as hereinbefore mentioned in which the resistance increases with increase of heat and the heat of course increases with increase in current.

On this wire is placed a bead 11 of material which will decompose rapidly on the incidence of heat of a predetermined value and during decomposition will itself give off sufficient heat to melt the wire. The operative element of the bead 11 is primarily magnesium powder which when decomposing rapidly will burn at a temperature of the order of 2000° F. and thereby immediately melt the wire 10 to break any circuit in which the wire 10 is connected.

Preferably the bead is formed of the following materials: 5% magnesium powder; 1.67% SiO₂ powder; 43.44% barium peroxide powder; 50% nitrocellulose lacquer dehydrated and placed on the wire so that it will be heated to initiate decomposition on the occurrence of the predetermined temperature or on the occurrence of a predetermined lower temperature for a predetermined minimum length of time.

The wire 10 must of course be sufficiently long to have the proper resistance during surges and to have the desired high temperature co-efficient in order to create an increased resistance on temperature rise. Accordingly as shown in Figure 2, the wire 10a is wound as a coil with the bead 11 on one of the turns of the coil.

As previously pointed out, preferably the coil should be supported only at its ends in order to reduce any

drawing off of heat by conduction to the supporting elements so that complete control is achieved by the rate of rise of temperature in the wire itself. Where, however, the wire must be sufficiently long to create correct resistance during surges the coil may require some mechanical support.

For this purpose I provide a coil form 12 as shown in Figure 3, generally of I shaped cross-section around which the high temperature co-efficient wire 10b is wound. By the utilization of the I form 12, a minimum of contact of the wire with the form 12 occurs and therefore a minimum amount of heat conduction from the wire to the coil form occurs.

In addition, the coil form 12 provides terminal securing means 13 which may be in the form of eyelets, rivets or any suitable means for securing the ends of the coil of wire 10b and the terminal connections 14, 14.

As shown in Figure 4, even the I shaped coil form of Figure 3 may be modified by adding the longitudinal indentations 15, 15 to the coil form 12a of Figure 4 to decrease the area of contact between the coil form and the wire.

In Figure 3 I have shown three beads 11a on the wire. The decomposition of any one of the beads will result in rupturing of the wire and interruption of the circuit. The utilization of three beads is a safety factor to ensure that at least one of the beads will operate to rupture the wire when the appropriate overcurrent-current value is achieved.

In Figure 5 I have shown in cross-section another modified coil form 12b in which the area of contact between the coil and the form are the longitudinal knife edges 16. This shape may be regarded as the simplest type of form having a star-shaped cross-section.

In Figure 6 I have shown another type of coil form 12c which consists of a rectangular member open on the center around which the coil may be wound. If desired also a groove 17 may be cut in the edges of the form over which the wire is wound in order to reduce further the area of contact between the coil and its form.

In Figure 7 I have shown one method of mounting the coil form 12 in a housing. The housing comprises a casing 20 having a base 21 and appropriate side walls, said casing being open at the end opposite the base. The cover plate 22 for the opening 23 of the casing has secured thereto in any appropriate fashion the coil form 12d. This coil form is shown as generally having the form of the coil form of Figure 3 but it will be obvious that it may have any of the other cross-sectional shapes already described.

The securing of the coil form 12d to the cover 22 ensures that when the cover 22 is placed over the opening 23 of casing 20, the coil form and the wire thereon will be spaced from the sides of the casing.

An opening 25 in the cover and an opening 26 in the base 21 of the casing will provide means for extending terminals from the coil on the coil form for connection purposes.

In Figure 8 I have shown a modification of the housing of Figure 7 wherein the casing 30 has a bottom wall 31 and an open end wall 32 at the side thereof opposite the bottom wall 31. The coil form 12e is here not secured to the cover but when placed in the casing the end 33 thereof is received in the matching internal recess 34 in the base 31 of the casing 30.

The cover 35 for the casing 30 also has a recess 36 which matches the end of the coil form. Consequently when the coil form 12e is placed in the casing with its end 33 in recess 34 and the cover 35 is placed on the casing, the coil form is spaced from the sides of the casing.

In Figure 9 I have shown another modified form of casing 40 having internal end recesses 41, 42 communicating with the open side 43 of the casing serving to position the edges 44 and 45 of the coil form. The re-

mainder of the interior of the casing 40 is cut away at 47 and 48 to provide an appropriate spacing between the casing and the coil form. In this case the cover 49 when secured in place by any appropriate means merely encloses the casing while the coil form is spaced from the sides of the casing by the internal construction above described.

It will be obvious that any coil form may be used in connection with the casings of Figures 7, 8 and 9 as long as the internal elements of the casing are shaped to correspond to the cross-section or shaping of the coil form.

In Figure 14 I have shown a modified form of coil form and casing wherein the casing 50 is provided with ledges 51, 52 adjacent its base 53 on which the lateral edges 54 and 55 of the wide parts of the coil form 12f may rest with the coil 10b thereby spaced from the casing. The coil form 12f is provided with connecting terminal prongs 56, 57 to which the coil 10b is connected.

The cover 58 is provided with internal ledges 59, 60 corresponding to the ledges 51, 52 of the casing to cooperate therewith in spacing the coil 10b from the side walls of the casing.

The cover is also provided with a pair of openings 61, 62 through which the prongs 56, 57 extend to enable the unit when assembled to be connected in circuit. The terminals used in connection with the casings of Figures 7, 8 and 9 may also be in the form of prongs connected to the eyelet or terminal elements 14 of the coil forms in any of those structures.

The prongs 56 and 57 readily extend from the side of the casing as shown in Figure 14 or from the end of the casing as shown in Figures 9 and 10 and may then be used not only to effect a connection with the appropriate socket but also to key appropriate fuses for insertion only in appropriate sockets.

Thus, as shown in Figure 11, chassis 70 may be provided with one pair of sockets 71 and a second pair of differently spaced sockets 72. If the combined fuse and current limiting resistor of my invention is arranged so that each rating thereof will have a different spacing between the prongs 56, 57 and that each socket for that rating in the chassis of Figure 11 will have each opening matching the spacings of the units to be inserted therein, then only the correct unit may be inserted in a particular pair of socket openings.

In addition, as shown in Figures 12 and 13 my novel unit may be provided with a key 80 cooperating with an appropriate keyway 81 on the chassis 82 of Figure 13. The keyway itself may also carry the circuit connecting elements or may be used in addition to the circuit connecting elements 56, 57 of Figure 10.

The keyways for any particular size or rating of combined fuse and current limiting resistor will be different from the keyways and corresponding keys for every other size and rating. Consequently by matching the keyway 81 and the key 80 for any unit, only the correct unit may be installed in the circuit.

In the foregoing I have described my invention only in connection with illustrative embodiments thereof. The various sizes of wire, thickness of wire and length of wire used, and the actual amount of flash material used in the bead will be determined by the various values which it is intended to protect.

In my novel bead arrangement, the barium peroxide used therein is the oxidizer, the magnesium powder is the burning element, the silica is used for dehydration purposes, while the nitrocellulose lacquer evaporates off.

It will be obvious of course that the size of wire determines the flash point. In the construction shown for instance in connection with Figures 3, 7, 8, 9 and 14, for a device intended to protect a 175 milli-ampere circuit with a 500 milli-ampere flash point, I use a 22 ohm resistor made of a nickel-iron alloy (Hi-Tempco or Balco No. 236 alloy), .0035" in diameter with 11 turns on a 1" form or approximately 22" of wire.

This will withstand a discharge of 165 mf. at 300 volts. Three beads are used, one on each end and one in the center. One bead will be sufficient but since the beads are placed on the wire by mass production methods, they may therefore vary somewhat in size. The utilization of three beads ensures that there will be at least one good bead.

In view of the many forms which my novel unit may take, I prefer to be bound not by the specific disclosures herein contained but only by the appended claims. It will also be understood that, contemplated within the term "coil" is any regular or series of regular curvatures or shapings of a length of wire, including zig-zag arrangements, which will make it possible to house or support a relatively long wire in a relatively short housing.

I claim:

1. A combined fuse and current limiting resistor comprising a coil of high temperature coefficient wire and a bead containing magnesium and barium peroxide on said wire, said bead having the characteristic of decomposing rapidly under predetermined heat conditions of the wire and itself generating sufficient heat to melt the wire when said bead decomposes.

2. A combined fuse and current limiting resistor comprising a coil of high temperature coefficient wire and a bead on said wire, said bead having the characteristic of decomposing rapidly under predetermined heat conditions of the wire and itself generating sufficient heat to melt the wire when said bead decomposes, said bead being formed from magnesium powder, silica powder, barium peroxide powder, and nitrocellulose lacquer.

3. A combined fuse and current limiting resistor comprising a coil of high temperature coefficient wire and a bead on said wire, said bead having the characteristic of decomposing rapidly under predetermined heat conditions of the wire and itself generating sufficient heat to melt the wire when said bead decomposes, said bead containing a magnesium salt, a peroxide salt and dehydrating agent.

4. A combined fuse and current limiting resistor comprising a coil of high temperature coefficient wire and a bead on said wire, said bead having the characteristics of decomposing rapidly under predetermined heat conditions of the wire and itself generating sufficient heat to melt the wire when said bead decomposes, and an I-section form for said wire coil, said form having a web effecting recesses adjacent a major portion of the coil, said recesses extending between parallel edges of the form supporting the coil and reducing the area of heat conductive contact between the form and the wire of the coil, the coil thus having substantially parallel and linear wire runs, said bead being on one of said runs.

5. A combined fuse and current limiting resistor comprising a coil of resistance wire and a form on which said coil is wound, said form having a recessed portion and said coil having runs of wire disposed across said recessed portion; and a bead of material rapidly decomposable under predetermined heat conditions on each of a plurality of said runs.
